UNITED STATES PATENT OFFICE.

HARVEY F. HOLLISTER, OF SPENCER, IOWA.

CONDENSER AND COOLER.

Application filed February 4, 1924. Serial No. 690,465.

It is generally known among automobileists that in motoring up a steep grade, through heavy snows, on a long uninterrupted trip, or under any other condition requiring a constant and heavy strain upon the engine that the water within the cooling system becomes exceedingly hot, oftentimes beyond the boiling point. Such a condition, of course, necessitates the driver to rest his motor sufficiently to cool the water supply and oftentimes, to replenish a great deal of the water supply that has escaped through evaporation caused by boiling and steaming.

My invention relates to condensers for radiators of the type that may be readily applied or removed from the radiator, and has for an object to provide means for conserving the water supply of the radiator by avoiding the wastage thereof by evaporation or ejection through the overflow pipe due to expansion by heat, and the scope of my invention extends to whatever construction may be defined by or included within the terms or language of the appended claims.

In the drawing:

Figure 1 is a view in perspective of my improved radiator condenser as applied to a radiator;

Figure 2 is a central longitudinal sectional view thereof;

Figure 3 is a detail cross section on the line 3—3 of Figure 2, and

Figure 4 is a detail sectional view on the line 4—4 of Figure 3.

My invention, in the form of embodiment shown in the drawing and briefly described, comprises a novel condensing device 10, which may be used in connection with the ordinary or usual radiator filling cap 11. Although the condensing device 10 may be of any desired form or shape, I have illustrated it as conforming generally to the contour or outline of the radiator to which it is attached.

The condenser 10 consists of an upper compartment 12 and a lower compartment 13, and a plurality of vertically extending tubes 14 providing communication between the compartments. Water-tight connection is of course, provided between the tubes 14 and the compartments 12 and 13 by soldering or any other desired manner.

For equalizing the cooling of the vertical

tubes 14, I provide a plurality of horizontally extending relatively thin metallic strips 15 which may be held in their spaced relation by soldering or other suitable means. These plates are, of course, provided with suitable openings for the passage of the tubes 14.

My improved condensing device is further provided with end walls 16 which not only connect the upper and lower compartments 12 and 13, but they serve to form a continuous and attractive supporting frame constituting the various desired designs.

The body portion of my condensing device 10 is provided with a downwardly extending tubular portion 17 and provided at its lower end with a reduced portion 17a, which is adapted to pass through the usual radiator cap 11, and is securely held in position by means of a suitable nut 18. By securing my improved device to the radiator cap in this manner, it will be seen that I may readily apply it to any desired form of cap, thereby rendering it a very necessary accessory.

For conveying the vapor from the upper portion of the radiator to my condenser I provide a vertically extending tube 19, which passes through the tubular portion 17, the chamber or compartment 13, the strips 15, and into the upper compartment 12. The tube 19 preferably is extended to within a short distance of the top of the chamber 12, and forms the outlet for the vapor from which point it is drawn downwardly through the tubes 14 in which the vapors are condensed. The liquid now passes down, collects in the lower chamber 13 and is returned to the radiator through the downwardly extending pipe 20, which is substantially of smaller diameter than the tube 19.

To prevent the premature condensing of the vapor as it passes through the tube 19, which would prevent the easy passage of the vapor through the tube, I pack asbestos or other suitable insulating material within the tubular portion 17 of the lower end of the compartment 13, as is clearly shown in Figures 2 and 3 as at 21.

It is to be understood that I may readily construct my device in various shapes or form in order to conform to the different designs or outlines of various hoods, which would be striking and effective in appearance. The precise construction of the con-

densing chamber of my improved device may also be varied without departing from the spirit of my invention.

I claim:

5. 1. A condenser for radiators, comprising a radiator cap provided with an opening, a casing having an upper and lower chamber, a tubular portion secured to the lower end of the casing and adapted to pass through said opening in the cap, condensing means interposed between said chambers and communicating therewith, a tube for each of said chambers extending downwardly through said tubular portion and packing within the tubular portion and surrounding said tubes.
10. 2. A condenser comprising an extension

formed at one end to be removably secured to a radiator cap, a lower header carried by such extension, cooling tubes rising from the lower header, an upper header carried by the upper ends of the cooling tubes, a vapor-feeding pipe leading vertically throughout the condenser and terminating immediately below the top of the upper header, and a condensate tube leading through the extension and terminating flush with the bottom of the lower header, the feeding pipe being of greater diameter than the condensate tube and of an unrestricted diameter throughout its entire length.

In testimony whereof I affix my signature.

HARVEY F. HOLLISTER.
